DESIGN FOR A PICTURE CARRYING SERVICE PLAQUE

George M. Diehl, Pleasantville, N. J.

Application March 6, 1942, Serial No. 106,098

Term of patent 3½ years

To all whom it may concern:

Be it known that I, George M. Diehl, a citizen of the United States and resident of Pleasantville, New Jersey, have invented a new, original, and ornamental Design for a Picture Carrying Service Plaque, of which the following is a specification, reference being had to the accompanying drawing, forming part thereof.

Fig. 1 is a front elevational view of a service plaque embodying my invention; and

Fig. 2 is a side elevational view of the service plaque shown in Fig. 1.

What I claim is:

The ornamental design for a picture carrying service plaque, substantially as shown.

GEORGE M. DIEHL.
